All Office Actions, U.S. Appl. No. 29/665,508.

Primary Examiner — Karen S Acker*(74) Attorney, Agent, or Firm* — Gary J. Foose**CLAIM**

The ornamental design for a sheet with pattern, as shown and described.

DESCRIPTION

The sole FIGURE is a front view of a sheet with pattern. The dashed broken lines shown in the drawings represent unclaimed structure or features that form no part of the claimed design. The dot-dash broken lines represent boundaries of the claimed design; the dot-dash broken lines themselves form no part of the claimed design.
